UNITED STATES PATENT OFFICE.

JAMES B. GRANT, OF NEW YORK, AND ALLAN MASON, OF BROOKLYN, N. Y.

PROCESS OF REFINING PETROLEUM.

SPECIFICATION forming part of Letters Patent No. 339,545, dated April 6, 1886.

Application filed June 30, 1885. Serial No. 170,252. (No specimens.)

To all whom it may concern:

Be it known that we, JAMES B. GRANT, of the city, county, and State of New York, and ALLAN MASON, of Brooklyn, in the county of 5 Kings and State of New York, have invented certain new and useful Improvements in Process of Refining Petroleum and other Oils, of which the following is a specification.

We have discovered that oils commonly known as "petroleum," procured directly from borings connected with favorable strata in the earth, and also oils which are obtained from coal, shale, bituminous schists, or other analogous hydrocarbons usually classified as 15 "oils," and to which our invention particularly refers, have somewhat of the nature or peculiarities of vegetable oils, and either in their crude form or partially refined or separated by other processes may, by rapid and violent 20 agitation in the presence of the vapor of water with sufficient heat uniformly applied and subsequent rapid condensation, be refined or manufactured into one practically uniform grade of oil of high fire-test, suitable for illuminating purposes.

We will describe our invention as applied to the treatment of crude petroleum. We receive the petroleum into a vacuum-retort, and meet it upon its reception therein with a 30 stream of live steam under sufficient pressure to thoroughly mix the vapor of water with the oil and instantaneously force the whole mass into a vacuum-condenser arranged to receive it, from whence it is pumped or allowed to flow into a tank.

We have discovered and demonstrated that the receiving of the petroleum into the vacuum-retort and striking it with such force with the vapor of water (thus rapidly atomizing 40 and evaporating the entire mass) without separating into any of its elements, and subsequently condensing it and separating it from the water, the water retains the impurities and undesirable portions of the oil, leaving us 45 the product described and desired. There may be chemical changes, and the operation of certain natural laws in producing these results which we cannot explain, but the effect is certain.

50 It is well known that natural products are always superior to artificial.

The difference between our process and the

various processes now in vogue is very similar to the difference between distilling and filtering water. It is also well known that the various 55 products of distillation can never be again resolved into the natural product from which they were produced.

We dispense with the ordinary destructive or fractional distillation.

We obtain a much higher percentage than usual of the grade of oil most desired. In fact, when no accident occurs and everything works properly, we convert all the crude product, except the undesired portion washed out 65 of it by the force and the vapor of water, into illuminating-oil of a high fire-test.

We have made provision for accidents and irregularities, which will be described hereinafter.

The evaporation of the petroleum is effected by uniform steam-heating, and also by mingling steam intimately with the petroleum, accompanied by violent mechanical action. The steam is employed in its natural state, by 75 which we mean not superheated. The temperature will be from 212° to 300° Fahrenheit. The entire vaporous mass composed of water and petroleum is instantaneously forced into a surface-condenser, where it comes in contact 80 with metallic surfaces kept at a low temperature by a liberal flow of water between the pipes or other elements of which the condenser is composed. We present the steam to the petroleum in the form of a jet, having such 85 force and being so presented to a properly-shaped nozzle that it will draw up the petroleum from a level a little below. Such devices have been long known for atomizing perfumery. Such have been applied in various 90 stages in the treatment of oils for producing vapors, but always for the purpose of destructive or more or less fractional distillation. We provide for making and maintaining a nearly-perfect vacuum in the retort or evaporating chamber. This greatly facilitates the vaporization and atomization without requiring so high a temperature as would produce destructive distillation or more or less fractional distillation. We have no deposit of oil 95 in the retort. The only material that can be possibly found in the retort will be obtained from accidental condensation of particles of the oil which are intended to be forced over,

but which, from said imperfect condensation, condense on the side of the retort, and are received into a pocket provided for the purpose. This would be one of the irregularities referred to, and for which provision has been made, as will appear further on.

The drawings show the novel parts with so much of the ordinary parts as is necessary to indicate their relation thereto.

10. The accompanying drawings form a part of this specification, and represent what we consider the best means of carrying out our invention.

15. Figure 1 is a general longitudinal section of the entire apparatus, partly in section. Fig. 2 is a cross-section on the line $x x$ in Fig. 1. Fig. 3 is a plan view of a portion provided for accident or irregularity.

20. Referring to the drawings, and to the letters of reference marked thereon, A is a steam-boiler, from the dome of which steam is led at high-pressure into a jacket or space between two shells, B B', of an evaporating and atomizing chamber or retort, b, which is surrounded by a body of sand, B³, serving to preserve and equally distribute the temperature.

25. Heat produced by fire in a furnace or chamber, B⁴, below aids to maintain the temperature of the steam in the jacket, notwithstanding the great consumption thereof due to the rapid evaporation of the petroleum going on in its interior.

30. A steam-pipe, A', conducts ordinary saturated steam at a high pressure from the boiler A to what we term a "double injector," a device located within the evaporating chamber or retort b. The construction and arrangement of the double injector is such that a pipe, C', leading upward from a tank, C, filled with crude petroleum, will, by the action of the strong blast of steam escaping from the pipe A', draw up the petroleum and mingle it intimately with the steam. The blast of steam atomizes and blows away the crude petroleum, and, aided by the heat received at a carefully-adjusted temperature from the inclosing-jacket, the high-pressure steam completely evaporates all the petroleum and carries it instantaneously to the neck D of the 35 retort and into the condenser E, with the exception of any minute particles which may, through imperfect condensation or other irregularity, drip down the sides of the retort through the small orifices t t t t t into the pocket B⁵ are allowed to run at intervals through the pipe B⁶ into the small tank B', from which, after being allowed to cool, it is allowed to run through the pipe B⁸ back into the tank C. Whenever this operation is per-

40. formed before the cock B⁶ is opened to allow the oil to run from the pocket B⁵ into a tank, B', the cock b' is closed to prevent the vacuum being disturbed, and in any event, when it becomes necessary to remove the oil from the pocket B⁵ before the steam and oil are again allowed to enter the retort through the pipes A' and C', as before set forth, the pump

E² is operated for some time in order to overcome any break in the vacuum that may have occurred. All the remainder of the petroleum is evaporated by the combined mechanical action and the uniform heat maintained,

70 as hereinafter described, aided by a nearly complete vacuum in the retort, which is maintained by means to be presently described.

75 The attenuated vapors of water and petroleum are conducted through the neck D to a surface-condenser, E, preferably what is known as the "Lighthall Condenser," having vertical tubes, the vapors being conducted through

80 the interiors of the tubes, and a liberal flow of cold water being circulated in the intermediate spaces. The effect is to condense the vapors, and again to produce nearly the original fluids—water and petroleum—which flow from

85 the bottoms of the several pipes and are drawn through a pipe, E', by an air-pump, E², operated by a steam-engine or other suitable power.

(Not shown.) The liquid being thus forced from the vacuum-retort and condenser is dis-

90 charged into a trough or long tank, F, in which it is allowed to separate. The water is drawn out through a pipe, F', and need not be further referred to. The oil is drawn out from a proper level in the tank F through one of a

95 series of pipes, g h i, into corresponding tanks or receptacles, G H I, the selection being controlled by an attendant who operates controlling-cocks g' h' i', according to the density of

100 the liquid. Under the best conditions the liquid will contain, first, water resulting from the condensation of the steam, which will easily separate at any subsequent stage by gravity on allowing the liquid to rest, and,

second, a practically uniform grade of refined

105 petroleum suitable for illuminating purposes. The condition in this respect is indicated by a hydrometer, which is applied in the ordinary or any suitable way to determine the gravity of the liquid.

110 Whenever the liquid is too dense for a good illuminating-oil, the attendant operates the cocks h' g' and discharges it through the pipe g into the tank G. Whenever the opposite condition obtains and the liquid is too light for a proper illuminating-

115 oil, the attendant opens the cock i' and discharges it through the pipe i into the tank I, excluding it from the other pipes, g h, and tanks G H; but if no accident or irregularity occurs in the process the oil will be all illu-

120 minating-oil of the required density and fire-test and will only be discharged into the tank H.

125 Tanks G I are a provision for irregularity or accident. When an accident or irregularity does occur to necessitate the oil being conveyed into the tank G or I, then the product in the tank G and I is returned to the tank C and the process repeated until the desired product is obtained. The illuminating-oil,

130 after standing a sufficient time in the tank H to allow the water to separate, may be removed by pumping or other ordinary or suitable means, and with or without further treat-

ment is ready for storage or use. This illuminating-oil is what we would always obtain unless some accident or irregularity occurs. We prefer that the pressure in the boiler A and in the jacket B B' shall be about two hundred and fifty pounds per square inch. A cock, A³, in the pipe A', operated to control the discharge of steam into the chamber b, may considerably lower the pressure at the points of discharge, while still leaving a sufficient force to act with the violence required in impinging against the particles of the petroleum and mechanically disintegrating the latter and driving them instantaneously into the condenser E. The flow of petroleum through the pipe C' is controlled by the cock C³. The fire in the furnace B⁴ may be maintained by coal, other ordinary fuel, or by crude petroleum applied by any desirable or economical means. The cold water may be circulated in the condenser E by a pump or other ordinary or suitable means. (Not represented.) On the admission of steam through the injector it meets the crude oil in the retort described *in vacuo*. The force of steam striking the globules of the crude oil, together with the peculiar effect due to its being *in vacuo* breaks them up completely. It further intimately mixes the oil with the vapor of water. The form of this double injector is such that the crude oil is impinged upon the steam passing through the upper injector, and the steam meeting it at that point under pressure incorporates itself in such a manner with the volatile portion of the oil as to wash and cleanse it without separating it in any way as when destructive distillation or superheated steam is used. It amalgamates the whole mass of vaporized oil and water. No separation of the component elements of either occurs. By the above means, together with the rapid condensation which follows, we produce one oil. Usually, and always when no accident occurs, an illuminating-oil is produced of a marketable fire-test, and a larger percentage thereof than is obtained by destructive or fractional distillation, or by the use of superheated steam.

We do not use various degrees of temperature to obtain several products procured by the ordinary methods; but by the peculiar arrangement of the steam-jacket and its surrounding of sand (thus maintaining uniformly and perfectly any degree of heat desired) and atomizing with saturated steam and pressure *in vacuo* force over into the condenser the entire mass, and cleanse the globules of oil while in their primitive and virgin condition, without separating the oil into any of its elements, thus refining without fractionally distilling petroleum and obtaining one product, which we find is marketable illuminating-oil of the required fire-test.

By our method of refining and rapid condensation *in vacuo* we prevent oxidation. The great rapidity with which the vapors are condensed will not permit of the free oxygen in the water being absorbed by the oil.

The inclosing of the retort b and the jacket B B' together with the neck D of the retort in sand, as shown in the drawings, is a very important part of the means employed to carry out our invention. It maintains the heat in the retort b at the uniform temperature desired, and is intended to prevent the imperfect condensation which would cause some of the particles of oil to drip through the orifices t t t t into the pocket B⁵. An indicator on the end or side of the pocket B⁵ indicates when there are sufficient drippings in the pocket to necessitate their removal as set forth. The tank C contains the crude petroleum or product to be refined, and the pipe C', when the crude oil is not so dirty as to require previous settling, could be inserted in any storage-tank from which the oil is flowing, or into any receptacle into which the oil is received from the well, and thus the refining process could be carried on at the wells or in their immediate vicinity.

In the practical operation of our invention, we first thoroughly heat the sand surrounding the steam-jacket B B' and retort b, operate the air-pumps, and allow steam to pass into the retort b from the boiler A, through the pipe A', test the vacuum and uniformity of heat obtained throughout the retort b, neck D, and the efficiency of the condenser E, and when all is working satisfactorily operate the cock C³ and allow the oil to be drawn into the retort b from the tank C. As soon as the oil enters the retort b from the pipe C', it is impinged upon by the steam entering continuously through the pipe A', and by the combined action of the air-pump referred to in the specification and the force of the steam is instantaneously conveyed to the neck D of the retort b and into the condenser E. This action is so rapid, and the intermixing of the saturated steam (at a temperature of 212° Fahrenheit and not over 300°) so thorough and complete that no decomposition of the oil nor separation into its elements or into different grades occurs, but the oil is taken from the condenser E, the same natural or virgin product that it was when it entered the retort b from the tank C, except that it is cleaned and purified by the thorough intermingling of the vapor of water, and the apparent affinity of the water for many of its impurities and undesirable portions. Why it proves to be illuminating-oil of such density and the required fire-test we need not explain, but such we find to be the result. Neither can we explain why petroleum, when being destructively distilled, must be submitted to a high degree of heat ere it will dissolve into any of its elements; but yet some of these elements when once eliminated from the parent body will remain a vaporous mass at a much lower temperature than that at which they were eliminated, even in some cases remaining a vapor or gas as low 32° Fahrenheit. Chemistry (while stating the fact) has never, so far as we have been able to discover, satisfactorily explained the reason or

cause. Observe, we do not destructively or fractionally distil. We do not decompose the oil.

Modifications may be made in the forms and proportions of the several parts of the apparatus. We can use other forms of condensers than Lighthall's.

The heat of the jacket B B' may be maintained by an active circulation of the high-pressure steam between it and a boiler, A, having sufficient heating-surface to maintain the temperature and pressure.

A single air-pump or set of air-pumps properly connected may maintain the vacuum throughout the retort b, neck D, and through a single condenser, E, as shown, or a series of condensers.

We can use hot air or superheated steam for the jacket B B' when the evaporation in the retort b is sufficiently rapid. In that case we would require to arrange a separate apparatus to superheat the steam, as the steam passing into the retort b must not be superheated.

We are aware that oil and steam have been introduced together in an atomized condition into a still, and thence led through a goose-neck into a condenser through the action of a vacuum-pump, and this, therefore, we do not claim; but a considerable condensation of the oil in the still, and a separation of the lighter

from the heavier has been contemplated and provided for in the process referred to.

The apparatus illustrated in this application is made subject-matter for a separate application filed August 13, 1885, No. 174,270.

What we claim as new is—

1. The process of refining petroleum and analogous oils, which consists in introducing the oil and steam together in an atomized condition into a heated chamber, and removing by means of a vacuum-pump substantially the whole of the mixed vapor of oil and steam, without sensible condensation in the retort, into a condensing-chamber, as set forth. 40

2. The process of refining petroleum and analogous oils, which consists in introducing oil and steam together in an atomized condition into a heated chamber and instantaneously removing substantially the whole of the combined vapor of oil and steam, by means of a vacuum-pump, into a condensing-chamber, as set forth. 45

In testimony whereof we have hereunto set our hands, at New York city, this 20th day of June, 1885, in the presence of two subscribing witnesses. 50 55
